UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR CRACKING OIL.

Application filed December 15, 1920, Serial No. 430,870. Renewed March 24, 1927.

This invention relates to improvements in process for cracking oil, and refers more particularly to method and means for utilizing and controlling the incondensable gas formed as an inevitable result of the cracking process, and more particularly to the utilization of the incondensable gas formed by the process itself, by passing it back through the heating tubes. In the present invention, the gas from each receiver goes to a common gas header, and is prevented from flowing back to the receiver, but instead is conveyed to a suitable reservoir where it is compressed and returned to the heating tubes.

In the drawings, the single figure designates a view partly in side elevation and partly in vertical section of a battery of stills, constructed in accordance with the present invention.

Referring to the drawings, 1 designates the various furnaces, in each of which is mounted a heating coil 2, as for example, a continuous coil of four-inch pipe several hundred feet in length. Each coil 2 is connected by transfer line 3, having throttle valve 4, to its expansion chamber 5. The inlet side of each coil is connected to a suitable feed pump 6, leading to any suitable source of raw oil supply. Each vapor chamber 5 is provided with a residue draw off pipe 7, controlled by throttle valve 8, and is also provided with a vapor outlet pipe 9, extending into the lower end of a dephlegmator 10, and provided with a spaced cap member 11, the arrangement being such as to permit the vapors to enter the dephlegmator 10, while preventing the reflux condensate from falling back into the expansion chamber. Instead the reflux condensate is drawn off through the line 12, having throttle valve 13, and leading back to the corresponding feed pump. Each dephlegmator is provided with suitable baffles 14, and at its upper end with a vapor outlet pipe 15, leading to condenser coil 16, seated in condenser box 17. The lower end of each coil 16 is connected to each corresponding receiver 18, which receiver has liquid draw off pipe 19, controlled by throttle valve 20 and pressure gauge 21 and liquid level gauge 22. Each receiver is also provided at its upper end with a gas outlet pipe 23, having throttle valve 24, which pipes 23 lead to a common gas header 25. In each pipe 23 is interposed an outwardly opening check valve 26, the arrangement being such that the incondensable gas can pass freely past the check valve 26 into the

header 25, but is prevented at all times from passing back from the header 25 to any of the receivers because of said check valve. The header 25 is connected to a compressor pump 27, which by means of line 28, delivers the incondensable gas under pressure into the gas receiver 29. This gas receiver 29 should, of course, be large enough to hold a very substantial amount of any incondensable gas, it being understood that the gas receiver here shown is only for the purpose of illustration. This receiver 29 is connected by a feed line 30, having main throttle valve 31. The feed line 30 in turn is connected by branch lines 32 having throttle valves 33 to the inlet side of the heating coils 2.

The process may be operated as follows: Oil, as for example, Kansas fuel oil, may be continuously fed through the various stills, and there subjected to a pressure of say 135 pounds and a temperature of 750 degrees F. While still in liquid phase the oil is delivered to the expansion chambers 5, where vaporization takes place. The generated vapors pass through the dephlegmators, where they are subjected to reflux condensation, and the reflux condensate returns to the heating tube for further treatment. The still incondensed portion of the vapors passes thence to the final condenser and receivers. The incondensable gas escapes from all of the stills to the common gas header, and thence is delivered by the compression pump to the gas reservoir and returned, if desired, to any or all of the heating coils. It is to be understood that it may not be desirable in all cases to continuously return the incondensable gas from the reservoir to the stills, and it is to be understood that each unit of the battery is complete in itself and constructed exactly alike and maintains its own pressure over its own generated vapors and is not subjected to any back pressure from the gas header on the receivers. In other words, the incondensable gas is prevented from flowing backwardly through the system at all times.

I claim as my invention:

1. A process of treating hydrocarbon oils, consisting in heating the oil in a plurality of independent units, in dephlegmating the evolved vapors, in continuously returning the reflux condensate to each heating unit for re-treatment, in condensing the vapors resulting from such dephlegmation and in collecting the resulting distillate, in passing the un- 110

densed gases produced in each unit to a common header while preventing the return of incondensable gases from said header into any one of said units, compressing the incondensable gases collected in said header and in returning said compressed gases in regulated quantities to the raw oil treated in each unit.

2. A process for treating hydrocarbon oils comprising heating the oil in a plurality of independent units, dephlegmating the evolved vapors, condensing the vapors uncon-

densed by such dephlegmation and collecting the resulting distillate, passing the incondensable gases produced in each unit to a common receiver while preventing the return of incondensable gases into any one of said units, compressing the incondensable gases collected in said receiver and returning said compressed gases in regulated quantities to selected units to facilitate the conversion of the oil therein.

GUSTAV EGLOFF.
